UNITED STATES PATENT OFFICE.

ALEXANDER P. WHITE, OF CALDWELL, NEW JERSEY.

BUILDING LATH.

Application filed November 29, 1916. Serial No. 134,143.

To all whom it may concern:

Be it known that I, ALEXANDER P. WHITE, a citizen of the United States, residing at Caldwell, in the county of Essex and State 5 of New Jersey, have invented certain new and useful Improvements in Building Laths, of which the following is a specification.

This invention relates to a new and practical building material particularly useful in fire-proofing construction, especially adaptable as a lathing for walls, partitions and the like.

Primarily the invention contemplates an improved building material of the character referred to which possesses lightness as well as strength and has many advantages structurally and commercially over the ordinary wooden lathing, and metal lathing of the woven wire type. Accordingly, to this end the invention contemplates a novel combination of metallic and non-metallic members to provide a lath-fabric which effects great saving in metal.

In carrying the foregoing general objects into effect, the present invention has in view a novel and useful non-metallic filler element, which may be so distributed and arranged throughout the entire structure as to materially reduce the quantity of metal used, while at the same time serving to partly cover the spaces between the metal members, thus presenting a surface that can be readily and economically plastered with a minimum quantity of plastering material. Furthermore, it is proposed to so construct the non-metallic elements of the lath that they will not be affected by moisture from the plastic wall or surfacing material, and consequently will not warp or bulge in the wall before the plaster is dry and produce objectionable undulations and consequent cracks such as are frequently caused by the buckling of some types of non-metallic lath materials.

Another object of the invention is to provide a fabricated lathing structure, wherein the non-metallic filler members may be utilized as weft or warp members in the woven fabric in any desired number and arrangement, together with ordinary wire weft and warp elements of the fabric.

With the above and other objects in view which will more readily appear as the nature of the invention is better understood,

the same consists in the novel construction, combination and arrangement of parts hereinafter more fully described, illustrated and claimed.

A preferred and practical embodiment of 60 the invention is shown in the accompanying drawings, in which—

Figure 1 is a plan view of my improved lath structure.

Figure 2 is a detail horizontal cross-sectional view on the line 2—2 of Figure 1.

Figure 3 is an enlarged detail perspective view of one of the non-metallic members of the lath.

Figure 4 is a perspective view showing 70 how the stock from which the non-metallic members are made may be formed.

Figure 5 is a perspective view illustrating one method of forming the slat-like non-metallic members of the structure. 75

Similar reference numerals designate corresponding parts throughout the several figures of the drawings.

A lathing structure embodying the present invention generally includes the longitudinal warp members 1 having combined therewith a plurality of weft members 2, and also the weft members or fillers 3 which are of a non-metallic character.

In the embodiment shown in the drawings, it will be observed that the several parts of the improved structure are adapted to be woven or fabricated together by any suitable process or machine, and are usually assembled in the same structure by a simple 80 weaving process. However, it will be understood that it is not the purpose of the present invention to be limited to any particular manner of assembling or combining the warp and weft members of the structure, 85 nor to the number and arrangement of the metallic and non-metallic members employed, but the idea of the present invention is to provide a novel composite filler element which may be freely utilized to 90 eliminate a considerable quantity of metal and at the same time provide a structure with improved capacity to receive and hold plaster. Therefore, the invention centers 95 in the use of a fabricated lath structure 100 including a plurality of non-metallic filler elements 3 of novel character and form.

Primarily, each non-metallic or filler element 3 is of relatively flat or slat-like formation, being considerably wider than it is 110

thick, and consists of the fibrous strip elements *a* and an intermediate cementitious or artificial stone core or body *b* as shown in Figure 3. The said outer fibrous elements 5 *a* are preferably sheets of paper of suitable grade and thickness treated or painted with a fireproofing and water-proofing composition, such, for instance, as an emulsion of ordinary paint and silicate of soda, which 10 would also have the effect to add stiffness and strength to the paper body. One or more sheets of paper may be utilized in forming the filler elements, but to insure stability, it is preferable to employ separate 15 sheets consolidated with a cementitious composition in the manner to be explained. That is to say, according to the present invention, a preferable and convenient embodiment thereof involves the use of separate 20 sheets of fibrous material designated by the reference letters *a*—*a* in the drawings, which, regardless of the fact of whether or not they are preliminarily treated with the fire-proofing and water-proofing 25 solution, are combined with a layer of cementitious material intimately united thereto, and constituting a core or filling between the same. This intermediate artificial stone core or filling may consist of 30 any suitable composition, such for instance, as a mixture of suitable proportions of asphaltum and silicate of soda which are thoroughly miscible to form a rigid homogeneous mass when hardened.

35 Heretofore, one of the chief objections to embodying non-metallic elements with metal elements in a lath-fabric, especially if the non-metallic elements were of a fibrous nature, has been the tendency of the fibrous 40 material to absorb moisture from the plastic wall material, thus causing buckling and warping which would distort the metallic elements, and cause the lath to buckle and bulge in the wall and produce an uneven 45 surface. Accordingly, by way of eliminating the objection to the presence of non-metallic elements in combination with metallic elements in a woven wire fabric, and still retain the advantages of the non-metallic elements, it is proposed to provide the 50 same with a multiplicity of perforations, such, for instance, as the relatively large openings *c*, and the more numerous smaller openings *d*, whereby the body of fibrous 55 material is materially reduced in each non-metallic element of the lath, thereby not only reducing the liability of moisture causing the fibrous sheets to buckle or warp, but at the same time also providing key-openings 60 for the plastic wall material.

Accordingly, it will be apparent that the non-metallic weft elements 3 are provided with a plurality of area-reducing openings, which break up the body of fibrous material in the non-metallic elements, so that if

any moisture reaches the fibrous body it will have a relatively small body to act upon, and be without energy to swell enough to produce undulations in the wall. Moreover, the holes permit swelling to take place 70 without disturbing the plaster body.

Referring now to Figure 4 of the drawings, illustrating one manner of forming the fibrous filler or unit elements, it will be observed that the fibrous sheets *a*—*a* heretofore referred to, have consolidated therewith the intermediate filling of cementitious material, which, when set and hardened constitutes a substantial reinforcement of the filler element. After the outer facing sheets become united with the stone-like filling, the entire sheet of material may be a suitable cutting and punching operation, whereby the filler elements are cut therefrom, as shown in Figure 5 of the 85 drawings, and the area-reducing openings are formed therein, or the paper sheets may be first perforated if that was found to be desirable. It will be understood that a single piece of paper capable of being 90 impregnated with cementitious material may be used instead of two sheets with the cementitious material between them.

In connection with the making of these non-metallic filler elements, it will, of course, be also understood that the composition of the filler may be varied to suit changing requirements of use and conditions of manufacture, nevertheless, the composition stated is entirely practical, and with 100 regard to the fibrous elements, it may be noted that any heavy substantial paper may be utilized. The weft elements thus constructed present a reinforced and stiffened non-metallic member, which not only presents an extended plastic supporting area, but by reason of its relatively large and imperforate surface, offers an extremely efficient plaster keying base, while at the same time contributing considerably to the 110 strength and reinforcement of the entire fabric owing to the large area of frictional contact for engagement with the wire elements, as distinguished from a mere point of contact such as exists between the wire 115 warp element and wire weft elements.

Without further description, it is thought that the many features and advantages of the invention will be readily apparent, and it will, of course, be understood that various 120 changes in the form, proportion and minor details of construction may be resorted to without departing from the spirit of the invention or scope of the appended claims.

I claim:

1. A lathing structure comprising interwoven metallic and non-metallic members, each non-metallic member being of flat strip-like form, and consisting of outer water-proofed facing elements and an in-

termediate filler of artificial stone material, said member having therein a plurality of body-reducing openings.

2. A lathing structure comprising interwoven metallic and non-metallic members, each non-metallic member consisting of outer water-proofed paper facing elements, having artificial stone reinforcing cores

therebetween, and having a plurality of body-reducing openings therein.

In testimony whereof I hereunto affix my signature in the presence of two witnesses.

ALEXANDER P. WHITE.
